UNITED STATES PATENT OFFICE.

MAXIMILIAN J. L. TOWLER, OF DETROIT, MICHIGAN.

DETACHABLE CALK FOR HORSESHOES.

SPECIFICATION forming part of Letters Patent No. 487,038, dated November 29, 1892.

Application filed April 22, 1892, Serial No. 430,218. (No model.)

To all whom it may concern:

Be it known that I, MAXIMILIAN J. L. TOWLER, a citizen of the United States, residing at Detroit, in the county of Wayne and State 5 of Michigan, have invented certain new and useful Improvements in Removable Calks for Horseshoes, of which the following is a specification, reference being had therein to the accompanying drawings.

10 This invention refers to the peculiar construction and arrangement of horseshoes, whereby the calks on a horseshoe may be readily replaced when worn out with new calks without taking off the shoe.

15 My invention especially refers to calks for use in winter, where it is especially desirable to have ready means at hand to prevent horses from slipping.

In the present state of the art removable 20 horseshoe-calks are well known; but certain features of my improvement will be found new and have been especially designed to overcome certain important defects which are urged against the constructions now found in

25 the market and which have always been in the way of a more extended use of these devices. One great objection which I have found is that the calks are always getting loose and often become lost. This is easily explained

30 when it is considered that some horses have a habit of striking their feet very hard on the ground, either when going fast or when restless in standing, and when the ground is hard or frozen the calks will in time get loose with 35 any ordinary fastening. If the calk itself screws into the shoe, it is liable to displacement by getting turned; but the worst feature is that if such calks are worn down the stump remaining in the socket can hardly be taken

40 out without taking off the shoe. Another objection against all calks in use now is that they soon become dull and new calks have to be put in if the condition of the ground requires it. My invention is intended to over- 45 come these objections; and to this end my invention consists in certain features of construction which I will now proceed to describe in connection with the annexed drawings, in which--

50 Figure 1 is a bottom plan view of a horse-shoe provided with my improved removable

calks. Fig. 2 is a section on line *xx*, Fig. 1, the section being also shown reversed from the natural position of the shoe. Fig. 3 is an elevation of one of the calks shown in the 55 same position as in Fig. 2, without being fastened to the shoe, however. Fig. 4 is a perspective view of one of the calks, looking at its under side.

My removable calks, of which I use three 60 on each shoe, are all alike and interchangeable and are struck up of sheet metal between dies. I preferably use a blank cut from steel plate to the required size to form the whole calk in one piece by being shaped between suitable dies. As the process of shaping such articles in this manner is well known in the art, I do not deem it necessary to describe it here in detail, as it does not form any part of my invention. The peculiar form, 65 however, in which such calks are shaped comprises the essence of my invention, and to this end each calk consists of a base portion *a*, which forms the bearing of the calk against the under side of the shoe. This base portion 70 has the peculiar feature of being slightly curved, (or double inclined,) so that the side intended to come in contact with the shoe is convex, as shown in Fig. 3, where the dotted line is intended to represent the bearing-face 75 of the shoe. Suitable holes *b* for two screws are formed in this base portion.

At the front edge the calk is formed with a standing flange *c*, which is also preferably curved to conform more or less to the outline 80 of the shoe, and this flange is continued around the ends to form the tapering wing-flanges *d*. At or near the middle the flange *c* is made with a deep bend or corrugation *e*, which also preferably extends into the base portion. 85 Screw-holes are tapped into the shoe to receive the screws *f*, by means of which the calks are secured to the shoe.

In practice, the parts being constructed and arranged as shown and described, they operate as follows: In the first instance it will be seen that the calks have a degree of elasticity or spring which accomplishes the important object of lessening the liability of the calks becoming loose. In this respect the bend *e* 90 acts as a spring to permit the screws to take up the curvature of the base-plate to act in

the well-known manner of a spring-washer against the heads of the screws to prevent them from becoming loose. The bend *e*, however, has another important function, in that it imparts to the flange *c* the necessary stiffness to withstand the severe usage to which it is necessarily subjected. It secures the important advantage of having the flange *c* uniformly thin, so that its wearing away will 10 make no difference in the sharpness of the calk. The end wings *d* also contribute to stiffen the flange *c*, and in connection with the bend *e* give the edge of the calk a desirable irregularity, which prevents the horse 15 from slipping even under the most unfavorable conditions. By tapering the end wings down to the base-plate they form corners at the extreme ends, which are made still more prominent by giving the end wings an inward 20 and downward slant, as shown in the drawings.

The screws are made, preferably, more or less flat-headed, whereby they are not liable to wear away, and thus still afford a good hold for the screw-driver when the calks have to 25 be renewed when worn down. If desired, the screw-heads may be countersunk, although I find it hardly necessary.

What I claim as my invention is—

1. The combination, in a horseshoe, of a 30 detachable calk integrally formed with a curved bearing portion or base and a standing flange formed on the outer edge thereof with a cen-

tral bend to form a spring for the curved base, substantially as described.

2. The combination, in a horseshoe, of a 35 detachable calk formed of sheet metal with a curved bearing portion or base having means for securing it to the shoe, a standing flange extending around the outer edge and ends of the base, and a bend in the middle of the 40 flange to form a spring for the base, substantially as described.

3. The combination, with a horseshoe, of three 45 detachable interchangeable calks formed of spring sheet metal, each provided with a curved base, a standing flange formed thereon and centrally corrugated, and two screws securing the calk to the shoe, substantially as described.

4. As a new article of manufacture, a 50 detachable horseshoe-calk struck up of sheet-steel and consisting of a curved base-section provided with apertures for fastening, a standing flange on the front edge, connected by tapering side wings to the ends, and a corrugation in the middle of said flange, substantially as described.

In testimony whereof I affix my signature in presence of two witnesses.

MAXIMILIAN J. L. TOWLER.
